TOY TELEVISION TELEPHONE

Raymond Lohr, Erie, Pa., assignor to Louis Marx & Company, Inc., New York, N. Y., a corporation of New York

Application February 3, 1936, Serial No. 62,147

18 Claims.

(Cl. 46—33)

This invention relates to toys, and more particularly to a toy simulating a television telephone.

The primary object of the present invention is to generally improve toy telephones by combining therewith television simulating apparatus. The latter includes a movable picture holder carrying a plurality of pictures. The pictures are viewed one at a time through a suitable sight window. It is not always convenient to locate the sight window at the picture holder, and in many cases the most suitable location for the sight window is either remote from or out of direct line of sight to the picture holder. One object of my invention is to make it possible to dispose the sight window and the line of sight thereto in most convenient location regardless of the structural location of the picture holder; and to this end I provide a suitable mirror system for reflecting a picture on the picture holder to the sight window. This construction has the important added advantage of increasing the apparent mysteriousness of the toy.

In accordance with a further feature and object of the invention, the pictures are so supported as to be exposed on both sides, and a picture is illuminated by a lamp arranged to throw the image of the picture on the mirror system. With this arrangement, the picture is in darkness and cannot be seen in the sight window except when the lamp is energized, which in turn is desirable in order to maintain the illusion of television.

In accordance with further features and objects of my invention, the picture holder is moved or controlled by a simulated calling dial; the calling dial is restored to initial position by suitable resilient means, but the picture holder is held in dialed position by appropriate detent mechanism; the dial and the picture holder are arranged coaxially and preferably in concentric relation to the base of the telephone structure, but the connection between the dial and the picture holder is not positive and instead is unidirectional in order to permit free return of the dial; and the picture holder is restored to initial position by separate restoring means when the telephone is hung up.

Still another object of my invention resides in the provision of a subdued audible sound during the apparent television picture reproduction, this sound being construed by the child as that accompanying the operation of the television apparatus. The sound is preferably produced by electrical buzzer means energized from the same

battery cell that is used to energize the picture lamp, and, in fact, a single switch is preferably used to produce both the visual and sound effect. In a toy of this character, it is also desirable to provide a bell for simulating the signal for an incoming call, and in accordance with the present invention a single structure is used both as a bell and a buzzer, the bell being rung in one position of a suitable switch or control device, and the lamp and bell being energized in another position of the control device which at the same time deadens or mutes the bell in order to produce a subdued buzzer sound.

Another object of my invention is to produce a realistic clicking sound during the operation of the calling dial. This clicking sound is preferably produced by mechanism which does not interfere with the desired immediate restoration of the dial to initial position.

To the accomplishment of the foregoing and other objects which will hereinafter appear, my invention consists in the toy telephone and toy television elements, and their relation one to the other, as hereinafter are more particularly described in the specification and sought to be defined in the claims. The specification is accompanied by drawings in which:

Fig. 1 is a front elevation of a preferred form of toy embodying features of my invention;

Fig. 2 is a transverse section taken in the plane of the line 2—2 of Fig. 1;

Fig. 3 is a partially sectioned plan view of the toy;

Fig. 4 is a plan view below the picture wheel, taken in the plane of the line 4—4 of Fig. 2;

Fig. 5 is a plan view above the picture wheel, taken in the plane of the line 5—5 of Fig. 2;

Fig. 6 is a detail of the picture wheel detent mechanism, and is taken in the plane of the line 6—6 of Fig. 5;

Fig. 7 is an enlarged section taken in elevation in the plane of the line 7—7 of Fig. 4;

Fig. 8 is explanatory of the operation of the control switch;

Fig. 9 schematically illustrates the mirror system;

Fig. 10 schematically illustrates a modified mirror system;

Fig. 11 schematically illustrates still another modified mirror system; and

Fig. 12 illustrates a somewhat similar arrangement without a mirror system.

Referring to the drawings, the telephone structure comprises, essentially, a base B, a hand-set H, and a supporting post P projecting upwardly

50 55

from base B and carrying the hand-set. The latter is connected to the telephone structure by a flexible cord C. A simulated calling dial D is mounted on top of base B. The structure generally resembles an ordinary telephone structure, but differs in being provided with a sight window T which in the present case is located on the post P facing the user of the telephone. The pictures or simulated television images are seen in the 10 window T.

Referring to Figs. 2 and 5, the pictures are carried at the peripheral portion of a picture holder or wheel W preferably arranged coaxially with and moved by dial D in order to bring any one 15 of the pictures on the wheel beneath post P. The picture is illuminated by a lamp L disposed therebeneath, and its image is thereupon thrown upwardly and reflected into window T by a suitable mirror system M. The energization of lamp L is controlled by a switch lever S, which lever may 20 also be used to control the energization of and, if desired, dampening of a calling bell. The optical system of this toy will be evident from inspection of Fig. 9.

Considering the arrangement in greater detail and referring more particularly to Figs. 2 and 5, the pictures 12 are carried at the peripheral portion of picture holder W, said picture holder comprising a main disc 14. Disc 14 is 30 loosely rotatably carried on a spindle 16 which is preferably coaxial with the dial D. The pictures are detachably secured to the holder, and for this purpose the outer edge of disc 14 is turned inwardly at 18 to receive the outer edges of the 35 pictures. A spring metal ring 20 is secured to the lower face of disc 14, said ring being provided with a plurality of outwardly projecting or radial fingers or lobes 22, there being one such finger for each picture space. The inner edge of 40 the picture is received between lobes 22 and disc 14. If desired, the periphery of wheel W may be cut away at each of the picture spaces, thus leaving interrupted T-shaped elements 24. This construction makes it possible to seize the outer edge 45 of the picture to facilitate removing or replacing the same. Access to the picture holder for this purpose is preferably obtained by means of a door 26, best shown in Fig. 4, the said door being hinged at 28 and held in closed position by an 50 appropriate latch 30. When door 26 is swung outwardly, the periphery of the picture wheel is exposed and the picture nearest the door is readily adjusted or changed. This is a desirable location for the door because it is concealed at the back 55 of the telephone structure, and, more importantly, because the picture being inserted on the picture holder may be illuminated and observed through the sight window in order to make sure that it has been placed in proper position. Moreover, 60 the door 26 affords access to the lamp L, in addition to the access which may, if desired, be provided through a bottom opening 32. (Fig. 4.)

The picture wheel is completed by an upwardly flanged detent disc 34, this disc being riveted on 65 top of disc 14 (Figs. 2 and 6). The picture wheel is normally urged toward initial position by an appropriate restoring spring 36 one end of which is secured to the wheel at 38, and the other end of which bears against an appropriate stationary 70 finger 40 projecting upwardly from the bottom 42 of the base. The picture wheel may be locked against the action of restoring spring 36 by a holding dog or pawl 44 (Figs. 5 and 6), said pawl being pivotally mounted at 46 on bearings de- 75 pending from the top wall 48 of the base. The

pawl is normally urged downwardly by an appropriate spring 50. The opposite end 52 of the pawl underlies the lower end of a vertically reciprocable trip rod 54, the said rod extending upwardly through the post P at a point outside the picture path. The general location of trip rod 54 is clearly shown in Figs. 1 and 3, and it will be seen that the upper end of the trip rod projects through the support 56 of hand-set H. When the hand-set rests on support 56, trip rod 10 54 is depressed, thereby elevating detent 44 and releasing the picture wheel for restoration to initial position. This initial position preferably carries no picture and may be left blank or given any desired legend (printed backward). 15

Dial D is formed from sheet metal and provided with a series of finger holes 58. The dial is normally moved to initial position by a restoring spring 60 the upper end of which is secured to the dial at 62, and the lower end of which is connected to the base at 64. An appropriate finger stop 56 may be mounted on the base, as is clearly shown in Figs. 1 and 3, thereby limiting the forward movement of the dial when selecting a particular number. The backward or restoring movement of the dial is limited by a suitable stop, here exemplified by a lug 68 depending from the bottom surface of the dial and coming into abutment with a stationary or stop lug 70 projecting upwardly from the base. 20 25

The dial is connected to the picture wheel with a uni-directional drive connection. Specifically, spindle 16, which rotates with the dial, carries an outwardly projecting drive finger 72 (Figs. 2 and 5) which moves against a driven lug 74 bent 35 upwardly from detent disc 34. When the dial is turned in a clockwise direction, finger 72 bears against lug 74 and causes the picture holder to rotate with the dial. When the dial is released, it is immediately restored to initial position by spring 60, but the picture wheel is locked against return movement by detent 44. This, of course, presupposes that the hand-set has been lifted from its support. 30

In order to produce a realistic clicking sound 45 as the dial is operated, I provide a toothed noise-making wheel 76 (Figs. 2 and 5) on spindle 16. A leaf spring 78 is fixedly mounted on the base at its outer end 80, while its inner end bears lightly against the teeth. It will be manifest 50 that a repeated clicking sound is produced as the dial is rotated. The relation between toothed wheel 76 and spring 78 is, however, made relatively light in order not to interfere with free movement of the dial and particularly the desired 55 restoration of the dial to initial position under the influence of spring 60.

The lamp is energized by a battery cell 82 which is preferably of the flashlight type. This battery cell is held in position by spring fingers 84 which are preferably bent upwardly from the bottom wall 42 of the structure. The bottom wall is cut away at 86 to facilitate replacement of the battery cell without removal of the bottom. A contact finger 88, bent upwardly from the bottom, bears against and grounds the base of the cell. The positive pole 90 of the cell bears against the upwardly turned end 92 of a suitable switch arm 94 (Figs. 4, 7 and 8). Switch arm 94 overlies and is secured to an insulation mounting 96 by means of an eyelet 98. Additional eyelets 100 and 102 are secured to the insulation strip 96 and act as switch contacts. 60 65 70 75

The switch is controlled by a switch arm S bent sidewardly at the outer end of an oscillat- 75

able rod 104 (Figs. 2 and 4). Rod 104 is journaled at its outer end in the peripheral wall 106 of the base, and at its inner end in a support 108. Beyond support 108 the rod 104 is bent sidewardly and carries an insulation disc 5 or wheel 110. By swinging the switch lever S from a position pointing to the left, as in Figs. 1, 3, 4 and 7, to a position pointing to the right, the insulation disc 110 is moved from the solid line position to the broken line position shown 10 in Fig. 8. By depressing the switch lever S toward the right, the switch arm 94 is moved downwardly against the contact 100, as is indicated by the broken line position 94' in Fig. 8. Contact 100 is connected to the bell and causes 15 the same to ring as though signaling an incoming call. When the switch lever is not forcibly depressed, the switch arm 94 rises to its normal position, as shown in Fig. 7, thereby opening both circuits. This takes place regardless of 20 whether the switch lever is directed generally to the right or generally to the left. When the switch lever is moved to the left and depressed, the insulation disc 110 bears downwardly on 25 switch arm 94 near its outer end and bends the same into engagement with both the contacts 100 and 102, as is shown by the solid line position in Fig. 8. Contact 102 is connected to the lamp L, and the lamp is accordingly energized. 30 At the same time the bell is energized.

At this time, however, the bell is muted to produce a relatively subdued buzzer sound. This result may be obtained by using a relatively soft knob or pad as a damper, as is disclosed in my co-pending application Serial No. 62,146, filed 35 concurrently herewith. In the present case, however, the desired result is obtained by moving the end 112 (Figs. 2 and 4) of the switch rod against the outer or free end 113 of a strip 114 40 the inner end of which is secured to the bell mounting at 116. It will be understood that strip 114 normally clears the gong 118 of the bell. However, when the switch lever is pressed downwardly in its left-hand position, the extension 112 45 of the switch rod depresses strip 114 into engagement with gong 118, thereby dulling its sound. The arrangement is preferably such that the sound then produced may be listened to for a substantial time, if desired, without excessive 50 inconvenience or annoyance, and the sound is used to simulate noise incident to the operation of television apparatus. It will be understood, of course, that this feature is not essential, and that the bell may, if desired, be used only as a calling signal, in which case the switch is modified 55 to close either the bell circuit or the lamp circuit alone.

The bell probably requires no detailed description, it being of conventional type and comprising 60 a magnet 120 for vibrating an armature 122 the outer end of which acts as a bell clapper 124. Armature 122 carries a conventional contact spring 126 cooperating with a fixed contact 128 in order to make and break the magnet circuit 65 as the armature vibrates.

The construction of the body of the toy is 70 relatively unimportant. Briefly, the base B is formed of an upwardly dished piece of sheet metal 48 the bottom of which is closed by plate 42. These parts are secured together by rolling 75 the edge of plate 42 over the edge of plate 48, as is indicated at 130 (Figs. 2 and 7). The post P may be formed of a single piece of sheet metal the lower end of which is secured to the top of

base B by appropriate tongue and slot connections one of which is indicated at 132 in Fig. 2.

The mirror system comprises, in the present case, only a single reflector or mirror M which may be made of glass but as here illustrated is 5 more simply made of a polished piece of sheet metal plated with a suitable finish. This mirror is held in place by suitable tongue and slot connections one of which is indicated at 134 in Fig. 2. The window T is cut through the front 10 wall of the post and is preferably closed by a piece of glass or other transparent material 136. The advantage of using glass in the window is to prevent undesired examination of the interior of 15 the toy.

The post is closed by a transverse plate 56 the center portion of which has downwardly bent flanges 138 and is secured to the upper end of the post by suitable tongue and slot connections 140. The outer ends of plate 56 are bent upwardly at 20 142, thus providing a support yoke which receives 25 and locates the hand-set in desired position.

The hand-set is, in the present case, made of sheet metal, but it will be understood that it may be made of other materials, for example molded 25 materials. The hand-set is connected to the base by a flexible cord C which is selected to simulate 30 a telephone cord.

A part of the telephone, in this case the top 35 surface of the base, is provided with a suitable card or other writing surface 144 (Fig. 3) on which the names of the various characters pictured in the apparatus may be listed, it being understood, of course, that the number to which each name is assigned corresponds to the appropriate dial number for bringing the picture over the lamp and into view when the lamp is lighted. The characters may be members of the child's 40 family, comic characters from newspapers, motion picture actors, etc.

The mirror system may, of course, be modified to meet any desired preference with regard to the location and direction of the simulated television image. The arrangement so far described is schematically illustrated in Fig. 9, and it will be seen that the image is cast upwardly and then reflected forwardly. This requires the observer to look directly at the telephone structure in an approximately horizontal direction. If it is desired to observe the image while looking downwardly at an angle, it is simply necessary to rearrange the picture and mirror system in a manner schematically illustrated in Fig. 10. Referring to that figure, it will be seen that the peripheral or picture-holding portion 150 of the picture wheel is bent downwardly at an angle 55 with respect to the central portion 152. The picture 154 is thus disposed at an angle, and the mirror 156 may be tilted upwardly to a vertical position. The picture image is thus reflected in 60 an upward direction, as indicated by the broken line 158.

This change in picture angle may be carried further to produce a vertically directed image. In such case, however, it is preferable to view the image from a forward point on the base of 65 the telephone, rather than from the post. Such an arrangement is schematically illustrated in Fig. 11, in which it will be seen that the peripheral picture-carrying portion 160 of the picture wheel is vertical or cylindrical. The mirror 162 is located at the forward part of the base and is inclined, as is indicated on the drawings. The lamp 164 is located within the picture drum. The image of the picture falling on mirror 162 is accordingly reflected upwardly, as indicated by the 70 75

line 166. Mirror 162 is located beneath a suitable sight window 168 formed in the top wall 170 of the base of the telephone. The movement of the picture wheel may, of course, be controlled just as previously described, by a coaxially arranged dial D located above the top of the base.

It is not necessary to use a mirror system when using a sight window located as is the window 168 in Fig. 11. The advantage of the mirror system in such case is primarily in making the operation of the toy less obvious; in making the image more mysterious; and in rendering it particularly difficult to observe movement of the picture wheel when the lamp is not energized. However, if these advantages are not deemed of particular importance, an arrangement may be used like that schematically indicated in Fig. 12. Referring to this figure, it will be seen that the picture wheel W is a flat wheel like that previously described. The sight window 172 is cut through the top wall 174 of the base at a point in front of the dial D and directly over the pictures on wheel W. The picture beneath the sight window may be illuminated by a lamp 176. The picture wheel is controlled or moved, just as previously described, by a preferably coaxially arranged calling dial D.

While the restoring springs and the mechanism for connecting the dial with the picture wheel have been omitted in Figs. 11 and 12, as well as in Figs. 9 and 10, it will be understood that a mechanical structure exactly like that described in connection with Figs. 1 through 6 may be employed.

It is believed that the mode of constructing and using, as well as the many advantages of my improved television telephone toy, will be apparent from the foregoing detailed description thereof. The pictures are carried on a concealed picture holder which is movable to permit selection of a desired picture. The pictures are detachably related to the picture holder so that pictures of personal interest may be employed. The picture holder is most advantageously located with respect to the telephone structure, and at the same time the sight window for the television image is located in any desired or convenient location even though visually remote from the picture holder. These are optically connected by a suitable mirror system, and the character of the image produced in the sight window is made distinct and luminous by using a special lamp.

The picture or person called is selected in a realistic manner by using a simulated calling dial for the purpose. This calling dial is itself immediately restored to initial position, just as is the case with a real telephone. However, the picture wheel is locked in the position last dialed and is there retained until the telephone is hung up, at which time the wheel is also restored to initial position, thus bringing the wheel and the dial again into registry. A clicking noise is produced as the dial is operated, but the mechanism producing this clicking sound does not interfere with free movement and restoration of the dial. A calling bell is provided in order to simulate the signal for an incoming call, and the calling bell and lamp are both preferably energized from a single flashlight battery cell. A noise is produced to simulate that attendant upon the operation of television apparatus, and this noise is conveniently obtained by dampening or deadening the sound of the calling bell. Various switching and dampening functions are desirably brought under the control of a single switch lever,

said lever preferably, though not necessarily, being arranged to energize and mute the bell whenever the lamp is lighted.

The optical system may be varied in many ways, a few of the variations and some advantages thereof being disclosed herein. The telephone simulation may be of the desk or upright type, instead of the hand-set type, in which case the restoration of the picture wheel to initial position may be obtained by hanging-up a receiver instead of a complete hand-set. These and other changes may be made in the structure disclosed, and it will therefore be apparent that while I have shown and described my invention in preferred forms, many changes and modifications may be made without departing from the spirit of the invention, defined in the following claims.

I claim:

1. A toy television telephone comprising a telephone structure, a picture holder movably mounted on and concealed within said telephone structure, said holder carrying a plurality of independent pictures of different persons likely to be called by a child on the telephone, a sight window into which a child playing with the toy may gaze to see a simulated television image, manually operable means to move the holder to optionally select a desired picture, and means including a reflector for reflecting the selected picture to the sight window. 20

2. A toy television telephone comprising a telephone structure, a picture holder movably mounted on and concealed within said telephone structure, said holder carrying a plurality of pictures of different persons likely to be called by a child on the telephone, a sight window into which a child playing with the toy may gaze to see a simulated television image, means to move the holder to select a picture thereon, means including a reflector for reflecting the selected picture to the sight window, and a lamp for illuminating said picture and thereby revealing the same in the sight window. 35

3. A toy television telephone comprising a telephone structure, a picture wheel movably mounted on and concealed within said telephone structure, said wheel carrying a plurality of independent pictures of different persons likely to be called by a child on the telephone, said pictures being printed on paper or other translucent medium, and said wheel being cut away at the picture itself, a sight window into which a child playing with the toy may gaze to see a simulated television image, means including a reflector for reflecting a picture on the picture wheel to the sight window, and a lamp for illuminating the side of said picture opposite the reflector and thereby revealing the picture in the sight window, the arrangement being such that the picture is not visible in the window when the lamp is extinguished. 50

4. A television toy comprising a housing structure, a picture holder movably mounted in and concealed within said structure, said holder detachably carrying a plurality of independent pictures, said pictures being of subjects which a child might wish to see by television, a sight window into which a child playing with the toy may gaze to see a simulated television image, 65 said window being out of the line of direct sight of the picture holder, means to move the picture holder to select a picture thereon, means including a reflector for reflecting the selected picture on the picture holder to the sight window, and a 70

- lamp for illuminating said picture and thereby revealing the same in the sight window, said picture being otherwise in darkness and not visible in the window, unless the lamp is lighted.
5. A toy television telephone comprising a telephone structure, a simulated calling dial mounted thereon, a picture holder rotatably mounted in and concealed by said structure, said dial and picture holder being in axial alignment, a restoring spring normally tending to restore the picture holder to initial position, lock mechanism for holding the picture holder in a position last dialed, and means to release said lock mechanism.
6. A toy television telephone comprising a telephone structure, a simulated calling dial mounted thereon, a picture holder rotatably mounted in and concealed by said structure, said dial and picture holder being in concentric relation, a restoring spring for restoring the dial to initial position, another restoring spring normally tending to restore the picture holder to initial position, uni-directionally operative means connecting the dial and picture holder, said means offering no resistance to restoring movement of the dial, and means for holding the picture holder in the position last dialed.
7. A toy television telephone comprising a telephone structure, a simulated calling dial mounted thereon, a picture holder rotatably mounted in and concealed by said structure, said dial and picture holder being in axial alignment, a restoring spring for restoring the dial to initial position, another restoring spring normally tending to restore the picture holder to initial position, uni-directionally operative means connecting the dial and picture holder, said means offering no resistance to restoring movement of the dial, lock mechanism for holding the picture holder in the position last dialed, and means to release said lock mechanism.
8. A toy television telephone comprising a telephone structure, a simulated calling dial mounted thereon, a picture holder rotatably mounted in and concealed by said telephone structure, a sight window disposed out of direct line of sight of the picture holder, means including a reflector for reflecting the picture to the sight window, means normally tending to restore the picture holder to initial position, and means for holding the same in position last dialed.
9. A toy television telephone comprising a telephone structure including a movable ear phone and a support therefor, a simulated calling dial, a picture holder rotatably mounted in and concealed by said telephone structure, a sight window disposed out of direct line of sight of the picture holder, a lamp for illuminating a picture, an optical system including a reflector for reflecting the illuminated picture to the sight window, means normally tending to restore the picture holder to initial position, detent mechanism for holding the same in position last dialed, and means operative in response to restoring the ear phone to its support for releasing said detent mechanism.
10. A toy television telephone comprising a telephone structure, a simulated calling dial mounted thereon, a restoring spring for said dial, a picture holder rotatably mounted in and concealed by said telephone structure, said picture holder being coaxial with said dial, uni-directionally operative means connecting the dial and picture wheel, a sight window disposed out of direct line of sight of the picture holder, means including a reflector for reflecting the picture to the sight

window, means normally tending to restore the picture holder to initial position, and means for holding the same in position last dialed.

11. A toy television telephone comprising a telephone structure including a movable hand-set and a support therefor, a simulated calling dial, a restoring spring for said dial, a picture holder rotatably mounted in and concealed by said telephone structure, said picture wheel being coaxial with said dial, uni-directionally operative means connecting the dial and picture wheel, a sight window disposed out of direct line of sight of the picture holder, a lamp for illuminating a picture, an optical system including a reflector for reflecting the illuminated picture to the sight window, a battery cell for energizing the lamp, means normally tending to restore the picture holder to initial position, detent mechanism for holding the same in position last dialed, and means operative in response to restoring the hand-set to its support for releasing said detent mechanism.

12. A toy television telephone comprising a telephone structure including a base, a simulated calling dial mounted on top of said base, a picture holder rotatably mounted within said base in coaxial alignment with said calling dial, and a sight window for observing a picture on the picture holder.

13. A toy television telephone comprising a telephone structure including a base, a simulated calling dial mounted on top of said base, a picture holder rotatably mounted within said base in concentric relation with said calling dial, a sight window for observing a picture on the picture holder, means to illuminate said picture, means tending to restore the picture holder to initial position, detent means to lock the picture holder in dialed position, and means to release said detent means.

14. In a toy telephone, a simulated calling dial, resilient means for normally restoring the same to initial position, a toothed wheel rotatable with said dial, and a noise producing element disposed in the path of said toothed wheel in order to produce a clicking sound during use of the dial, said means being incapable of locking the dial against the action of the restoring spring.

15. A toy television telephone comprising a telephone structure, a movable picture holder, a sight window for exposing one of the pictures thereon, a lamp for illuminating the picture, electrically operable means to produce a subdued noise, and a switch for simultaneously energizing the lamp and said means in order to produce a subdued noise during the simulated production of a television image.

16. A toy television telephone comprising a telephone structure, a movable picture holder, a sight window for exposing one of the pictures thereon, a bell, a battery cell, means to dampen the sound of the bell to a subdued buzz, and means for simultaneously making the picture visible and energizing and dampening the bell in order to produce a subdued noise during the simulated production of a television image.

17. A toy television telephone comprising a telephone structure, a movable picture holder, a sight window for exposing one of the pictures thereon, a lamp for illuminating the picture, a bell, a battery cell, means to dampen the sound of the bell to a subdued buzz, and a switch for simultaneously energizing the lamp and the bell in order to produce a subdued noise during the simulated production of a television image.

18. A toy television telephone comprising a telephone structure, a picture holder movably mounted in and concealed by said telephone structure, a sight window, a lamp for illuminating the picture in order to make the same visible in the sight window, a bell, means to dampen the sound of the bell, a battery cell, and a multiple-posi-
- 5

tion switch mechanism arranged to operate the bell in one position, and to energize the lamp and the bell and at the same time to automatically dampen the bell when moved to another position.

RAYMOND LOHR.
